UNITED STATES PATENT OFFICE.

CHARLES B. LANE, OF KNOXVILLE, TENNESSEE, ASSIGNOR TO DRAPER COMPANY, OF HOPEDALE, MASSACHUSETTS, A CORPORATION OF MAINE.

LOOM.

1,145,425.

Specification of Letters Patent.

Patented July 6, 1915.

Application filed November 12, 1913. Serial No. 800,620.

To all whom it may concern:

Be it known that I, CHARLES B. LANE, a citizen of the United States, residing at Knoxville, in the county of Knox and State 5 of Tennessee, have invented a new and useful Improvement in Looms, of which the following is a specification, reference being had to the accompanying drawing.

My improvement relates particularly to 10 cloth weaving looms having bobbin magazines or batteries similar to the No. 3 "Northrop" batteries on looms manufactured by the Draper Company, of Hopedale, Massachusetts.

The object of the improvement is to provide more efficient means for clamping and parting or cutting the filling thread between the cloth and the empty or nearly empty bobbin which is to be discharged 15 from the shuttle and give place to a new bobbin from the magazine or battery. For such cutting, looms of this type have thread clamping and parting instrumentalities comprising knives and accessories located 20 between the cloth and the "battery", which instrumentalities are moved automatically to the path of the thread when the reduced quantity of thread on the bobbin allows a "bobbin feeler" to set a "starting rod" 25 into motion, the knives being made to cut by the action of the "bunter" upon one of the knives, the "bunter" being mounted on the "lay" in position to engage and move a part closely associated with one of the 30 knives when the lay reaches its forward position, the position occupied by the lay when the bobbins are to be transferred. This leads to the clamping and parting or cutting of the thread as often as motion is 35 transmitted from the "shuttle feeler" for moving the knives to the thread path. As a consequence, the thread is at times clamped and parted or cut when the bobbin is not changed, so that the nearly empty bobbin 40 remains in the shuttle and is carried back and forth by the latter without paying out filling thread into the warp, which action causes defects leading to the grading of the cloth as "second". This defect is always 45 objectionable and especially so in the higher grade and expensive cloths.

Failure to discharge a bobbin from the shuttle and put another into its place may be due to any one of several causes. For ex-

ample, the portion of the battery immediately above the shuttle may, on account of neglect of the attendant, be empty, so that, although the mechanism which normally drives a full bobbin out of the magazine into the shuttle and against the empty or partially empty bobbin, goes through its movement without delivering a new bobbin into the shuttle; or even when the magazine is properly filled, it may fail to partially turn to bring a new bobbin above the shuttle, such failure being due to wearing or other derangement of the mechanism which normally turns the magazine far enough to bring a new bobbin above the shuttle. By means of my improvement the operation is so changed as to retain the bodily movement of the clamping and parting instrumentalities or knives and their accessories to and from the thread path and to actuate the movable knife to clamp and part or cut the thread only when the bobbin leaves the shuttle and another enters from the magazine. Thus the bobbin in the shuttle does not travel with a cut thread, and the shuttle does not travel without a bobbin, for the bobbin in the shuttle is forced outward only by the downward pressure of a new bobbin taking its place in the shuttle. In other words, the clamping and parting instrumentalities is actuated through the movement of a bobbin out of the magazine into the shuttle. It is the bobbin in the magazine which rocks the bobbin support.

My improvement involves the making of a combination which includes means for transmitting motion to the movable knife from a bobbin passing downward from the magazine into the shuttle. As a practical example of such an embodiment of my invention, I describe herein the "bobbin support" as a portion of the mechanism forming such connection between the knife and the bobbin being discharged from the magazine, such "bobbin support" being a spring-controlled rocking member heretofore applied below the lower portion of the inner end of the magazine in proper position to receive and support the end of the bobbin adjacent the knives when the bobbin reaches its position above the "shuttle box", 105 the inner disk of the magazine being surrounded by a stationary flange which serves to hold the inner ends of the bobbins in

notches in said disk until the bobbin reaches such position above the shuttle, at which place said flange is omitted and its place taken by the tilting or rocking "bobbin support", which support is held in its normal position by a spring and driven out of position by said bobbin when sufficient downward pressure is placed upon the latter by the mechanism heretofore used in such looms for driving such bobbins downward.

In the accompanying drawings, Figure 1 is a front elevation of a bobbin magazine or battery and accessory parts, the thread guide and holder and other portions being omitted; Fig. 2 is a section on the line, 2-2, of Fig. 1; Fig. 3 is a section on the line, 3-3, of Fig. 1; Fig. 4 is a section in the upright plane in which the bobbin support spring bolt lies; Fig. 5 is a section on the line, 5-5, of Fig. 4, looking downward; Fig. 6 is a detail plan of a portion of the knife actuating mechanism; Fig. 7 is an upright section on the line, 7-7, of Fig. 6, looking in the direction of the arrow; Fig. 8 is a section on the same line, looking in the opposite direction, the left-hand portion of said figure presenting the clamping and parting members; Fig. 9 is a section on the line, 9-9, of the Fig. 8, looking in the direction of the arrow; Fig. 10 is a section on the line, 10-10, of Fig. 8, looking in the direction of the arrow; Fig. 11 is an elevation of the left hand end of the clamping and parting mechanism shown in Fig. 8; Fig. 12 is a front elevation of the upper knife, detached from the other parts.

Referring to said drawings, A¹, is a portion of the right hand loom side. This and the left hand loom side (not shown) support the breast beam, A², only the right hand portion of which is shown. The two looms sides are joined to each other by the breast beam and the front and rear girts (not shown). The magazine or hopper is shown supported by the breast beam. The shuttle feeler and thread arm are shown supported on the right hand loom side.

For convenience in description, the portion of the machine to which the magazine is applied and at which the loom side, A¹, is located will be regarded herein as the right hand side of the machine, while the portion of the machine at which the breast beam is located will be considered the front of the machine, and movement toward the front of the machine will be called "forward" and movement in the opposite direction will be called "rearward."

The hopper stand, B¹, has a foot, B², resting upon the breast beam, A². A bolt, B³, and a bolt, B⁴, extend through said foot, and engage the breast beam, whereby the hopper stand is rigidly secured. The bobbin disk stud, B⁵, extends toward the right from the center of the hopper stand and is rigid

thereon. On said stud is located a sleeve, B⁶, held in place by a nut, B⁷, threaded on the stud. On the left hand end of said sleeve and rigid therewith is the bobbin disk, B⁸. Said disk has peripheral notches, B⁹. The hopper stand has a flange, B¹⁰, extending over the edge of the bobbin disk, excepting at its lower portion. The bobbin disk has on its right hand face a ratchet tooth ring, B¹¹. On the outer, right-hand end of the sleeve, B⁶, is the small end disk, B¹². On the left hand or inner face of the small end disk are radial bobbin holders, B¹³, corresponding in number and position with the notches, B⁹, in the bobbin box. These bobbin holders are plates supported yieldingly in a radial recess, B¹⁴, by expanding coiled springs (not shown). Each such holder receives the small end of a bobbin, C¹, the large end of the bobbin resting in a corresponding notch, B⁹, in the bobbin disk, B⁸.

In the opening in the flange, B¹⁰, is a horizontal, lower flange, B¹⁵, at the rear of which is a space between it and the rear, lower end of the flange, B¹⁰. Mounted on the rear end of the flange, B¹⁵, is a bobbin guide, B¹⁶. Rearward of said bobbin guide is the bobbin support, B¹⁷, which is journaled on the horizontal shaft, B²⁰, extending through an ear, B²¹, cast integral with the hopper stand. The space between the forward end of the bobbin support and the rear face of the bobbin guide is smaller than the large end of a bobbin, so that when, by the rotation of the disks, B⁸, and B¹², a bobbin is brought to said support and guide, the head of the bobbin can not pass between said guide and support, but must rest upon the latter until said support is depressed far enough to make said opening large enough for the downward passage of the head of the bobbin. At the left of the hopper stand is an ear, B²², in which is a slide bolt, B²³, bearing against an upward extension, B²⁴, on the bobbin support. Said bolt extends through said extension and has a head resting against the outer or front face of said extension. At its opposite end said bolt has a head and between said head and the ear, B²², is an expanding coiled spring, B²⁵, which bears against said head and against washers, W, interposed between said ear and said spring. Said spring tends to move said bolt rearward and upward, whereby the upward extension, B²⁴, of the bobbin support is drawn rearward and the bobbin support tilted so as to bring its forward portion into the horizontal position and in such relation to the bobbin guide as to make the passage between said guide and said holder too small for the passage of the bobbin head. Sufficient downward pressure upon said end of the bobbin holder overcomes the resistance of said spring and causes the tilting of

the bobbin holder and the downward movement of said end. Such downward pressure upon the bobbin support is exerted upon said holder through the bobbin resting 5 upon said support as will be hereinafter described. At the time such downward pressure is exerted upon said bobbin, the shuttle, C², (Fig. 2) is in position directly below said bobbin to receive the latter. The downward movement of said bobbin into the shuttle involves the forcing of the empty bobbin out of the shuttle, the upper bobbin being pressed with sufficient force to disengage the empty or lower bobbin from the 10 shuttle, the lower or empty bobbin being discharged through the bottom of the shuttle. 15 On the lower forward portion of the hopper stand is a horizontal sleeve, D¹, in which rests the transfer stud; D², secured rigidly 20 by a set bolt, D³, extending through said sleeve and binding said stud. Loosely surrounding said stud is a sleeve, D⁴, and rigid on said sleeve is the transferrer, D⁵, which is in the form of a hammer adapted to strike 25 downward upon the large end or head of the bobbin which is to be discharged from the magazine into the shuttle. On the outer end of the transferrer is a fork, D⁶, extending parallel to the transfer stud, D², until it is 30 opposite the outer portion of the lower bobbin and thence downward into position to strike the small end of the bobbin approximately simultaneously with the striking of the head of the bobbin by the transferrer, D⁵. 35 A coiled spring, D⁷, surrounds the sleeve, D⁴, and has one end secured to a collar, D⁸, rigid on the stud, D², and having its other end engaging the transferrer, D⁵, for the purpose of turning the latter upward and 40 forward away from the bobbin support into the normal or rest position. On the sleeve, D⁴, is a downward directed fork, D¹⁰, in which rests a shaft, D¹¹. An ear, D¹², surrounds said shaft between the arms of the 45 fork and is keyed to said shaft and supports the latch stand, D¹³. Said latch stand supports a latch finger, D¹⁴. On the latch finger is a horizontal lateral wrist, D¹⁵. The wrist, D¹⁵, connects with the latch setter as will be 50 hereinafter described.

The magazine rotates clock-wise, as viewed from the right of the machine, by steps equaling the distance between the axes of adjacent bobbins. The teeth on the ratchet tooth 55 ring, B¹¹, are the same in number as the notches in the bobbin disk. A hold back pawl, B²⁶, is pivoted to the hopper stand in front of the transfer stud, D², and extends upward in position to enter the path of 60 the ratchet teeth to prevent reverse movement of the magazine. On the transferrer, D⁵, is pivoted the feed pawl, D¹⁶. Said pawl extends rearward and upward and normally rests by its free end on the head of 65 the transferrer and is adapted to extend

into the path of the ratchet teeth. When the transferrer is returning from its downward stroke, said pawl engages one of the ratchet teeth and pushes forward and upward, the range of movement being far enough to turn 70 the magazine far enough to bring a new bobbin above the discharge throat. The transferrer is driven downward by the forward movement of the latch finger, D¹⁴, when the bunter, D¹⁷, on the lay, D¹⁸, is 75 carried forward by the forward movement of the lay.

Below the breast beam, A², the shuttle feeler bracket, E¹, is secured to the left hand face of the right hand loom side, A¹, 80 by means of bolts, E². A bolt, E³, extends through the rear end of said bracket and through a bushing, E⁴, and binds said bushing to said bracket. The shuttle feeler, E⁵, has a hub surrounding said bushing and shorter than the latter so that said hub may move endwise on said bushing. On the forward portion of the bracket are two diagonal arms, E⁷, between which lies the neck 85 of the shuttle feeler. Said arms incline toward the right, so that when said neck rises, it and the entire feeler are forced rightward. The latch setter, E⁸, is rigidly secured to the shuttle feeler rearward of the arms, E⁷, and extends horizontally 90 across the loom side and then forward. The forward-turned portion has a slot, E⁹, which receives the wrist, D¹⁵; on the latch finger, D¹⁴. The relative arrangement and dimensions of these parts are such as to 95 bring the latch finger into its lower or depressed position when the shuttle feeler is in its forward or rest position. When the shuttle feeler is moved backward, by the means to be hereinafter described, the latch 100 finger moves rearward and upward and correspondingly moves the wrist, D¹⁵, whereby the latch is rotated on the shaft, D⁷, until the rear end of the latch finger is in position 105 to be met by the bunter when the latter moves forward. This movement of the latch, it must be observed, is independent of any movement of the transferrer, D⁵, on the transfer stud, D². When the bunter moves forward, it strikes the end of the 110 latch finger and forces the entire latch bodily forward, whereby the transferrer is turned on the transfer stud, the rear portion or head of the transferrer striking 115 downward upon the bobbin which is to be 120 discharged from the magazine.

The shuttle feeler is turned rearward out of its position of rest by motion transmitted from the "starting rod", (not shown) through an arm (not shown) supported on 125 the starting rod. The left hand portion of said rod is connected with a reciprocating bobbin feeler which during each reciprocation of the shuttle across the loom reaches into the side of the shuttle and bears against 130

the filling on the bobbin. When the filling on the bobbin is reduced to a chosen quantity, said feeler causes or permits a partial rotation of said starting rod (which is a 5 rock shaft) in the proper direction to lift said arm. Said arm engages the wrist, E²⁸, which is rigid on the shuttle feeler, forward of the hub of the latter. A spring (not shown) is so applied as to tend to draw said 10 wrist downward. When the starting rod turns from its position of rest, said arm is raised, whereby the wrist, E²⁸, is raised, whereby the shuttle feeler is moved rearward out of its position of rest to the thread 15 path ready for cutting the thread and in position to prevent the shuttle from moving endwise toward the cloth after the shuttle has assumed its position beneath the magazine.

20 The upper, rear portion of the shuttle feeler extends into the shuttle path when the feeler is in its rearmost position and the shuttle and the lay are in the forward position or at "front center". The 25 shuttle feeler has a notch, E¹⁰, to receive the filling thread when the shuttle approaches the position to receive the new bobbin. The recess, E¹¹, in the left hand side of the outer portion of the shuttle 30 feeler receives a lower filling knife, E¹². The upper filling knife, E¹³, is pivoted on a screw stud, E¹⁴, extending horizontally from the left hand side of the shuttle feeler, the jaw of said knife standing, when it is in its 35 rest position, far enough above the lower knife to readily receive the filling thread between said knives. At the left of the upper knife is the filling knife guide, E¹⁵. The screw stud, E¹⁴, also extends through 40 said guide. At the left of said guide is a spring washer, E¹⁶, surrounding said stud. The head of the screw stud bears against said washer and causes the engagement of 45 the latter with the guide. Forward of the screw stud, E¹⁴, is a stud, E¹⁷, extending rigidly toward the left from the shuttle feeler into a large opening, E¹⁸, in the upper knife, E¹³, and into an opening, E¹⁹, in the guide, E¹⁵, the latter opening being of about 50 the same diameter as the stud, E¹⁷, so that the guide can not rotate on the screw stud while the larger opening, E¹⁸, in the upper knife permits rotation of the upper knife on the screw stud.

55 A block, E²⁰, is secured by its lower end to the forward portion of the left hand side of the upper knife and extends thence upward a short distance and there supports an upper trip pin or wrist, E²¹, extending horizontally 60 toward the right. At its lower end, said block bears a similar lower trip pin or wrist, E²², extending toward the left. The upper trip pin is engaged and lifted for moving the upper edge of the cutting knife downward. This occurs while the shuttle feeler 65 is in its rear position—the position at the thread path. The other trip pin is engaged and moves downward for tilting the upper knife in the opposite direction so as to raise its cutting edge away from the cutting edge 70 of the lower knife ready to receive the filling thread. Such movement is imparted to the lower trip pin while the shuttle feeler is moving rearward from its position of rest. In the path of said wrist is the trip, E²³. Said trip is pivoted on a screw bolt, E²⁴, supported by the thread holder arm, E²⁶, and a coiled spring, E²⁵, is coupled to said trip to tend to raise its forward end. The trip has an upper or oblique face, E²⁷, over 75 which the lower trip pin must pass when the upper knife is in the closed position, and the feeler moves forward to its position of rest. This involves the depression of said trip and the partial forward tilting of the thread holder arm, E²⁶, on its stud, E²⁹, against the stress of the contracting spring, E³⁰. This is the normal action. The knives are to be opened when the shuttle feeler moves in the opposite direction toward the thread path. Then the wrist passes beneath the trip and is forced downward by the latter. This leaves this wrist in position to let the shuttle feeler go through any number of reciprocations with no further movement of the wrist, 80 so lowered, and consequently there is no closing of the clamping and parting means until the clamping and parting means closing mechanism next described is put into action. Said closing mechanism, which, in 85 the form illustrated by the drawings, includes the upper trip pin, E²¹, constitutes the new portion of the mechanism herein described. The mechanism thus far herein described, excepting the upper trip pin or 90 wrist, E²¹, has been heretofore used in said looms manufactured by the Draper Company.

95 The movement of the upper trip pin for the closing of the knives is effected by means of a group of members one of which is a movable member extending into the path of the bobbin which is to be discharged from the magazine, and which during such discharge moves said movable member, and 100 which movable member is not moved by the action of the lay or the bunter or the trans- 105 ferrer or any other member without the intervention of such bobbin.

110 A bracket, G¹, rests upon the foot, B², of the hopper stand and surrounds the bolt, B³, and is secured by said bolt. Said bracket extends rearward and has at its rear end a bearing, G², which is horizontal and parallel to the magazine axis. In said bearing is a 115 rock shaft, G³. On the right hand end of said shaft is a finger, G⁴, said shaft extending through said finger and a set bolt, G⁵, extending through the base of the finger and binding the latter to said shaft. Said set 120

125 130

5 bolt permits the adjustment of said finger at different angles on said shaft. Said finger is set to bear against the head of the slide bolt, B²³, which is associated with the bobbin support, B¹⁹, as already described. A finger, G⁶, is applied rigidly on the left hand end of said rock shaft and extends downward and rearward in proper position to rest immediately below the upper trip pin 10 when the shuttle feeler is driven rearward to its rear limit—the position which it occupies when the filling thread is to be clamped and parted or cut and when the bobbin is to be discharged from the magazine. A coiled spring, G⁷, surrounds the right hand portion 15 of the bearing, G², and has one end extending beneath the bracket, G¹, and the other end beneath the finger, G⁴, for yieldingly pressing said finger upward toward or 20 against the head of the slide bolt, B²³. In the left hand portion of the bearing, G², is a notch, G⁸, and a pin, G⁹, is set rigidly on the rock shaft, G³, within said notch. The notch is of proper width to allow the desired 25 partial rotation of said shaft and no more.

Now the downward movement of such bobbin on the bobbin support will tilt the latter and drive the slide bolt, B²³, against the finger, G⁴, driving the latter downward and turning the rock-shaft, G³, and raising the finger, G⁶, whereby the upper trip pin is raised and the upper knife tilted to clamp the thread and bring the cutting edge of said knife down upon the cutting edge of 35 the lower knife. Then, as already described, when the shuttle feeler again moves forward, toward its position of rest, the lower trip pin passes over the upper face of the trip, E²⁴, the trip being depressed to allow 40 said finger to pass over, the knives remaining closed.

By test I have found that the power required for actuating my knife closing mechanism does not interfere with the discharge 45 of the bobbin from the magazine.

The cut is made during the movement of the bobbin out of the magazine. Hence the thread is clamped and parted or severed before the lower bobbin leaves the shuttle. Furthermore, since the head of the trans- 50 ferrer moves downward rapidly, it follows that, as is desirable, a quick movement is imparted to the upper knife.

The thread holder arm, E²⁶, serves in the 55 usual way to support the filling thread until the latter has been clamped and parted or cut by the knives already described and also by the temple knives at the selvage of the cloth.

As is the case in machines now in use, the 60 bobbin discharge path extends downward between the bobbin guide, B¹⁸, and the bobbin support, B¹⁹, and through a portion of the latter, and through and below the 65 shuttle and, as above indicated, the bobbin

support is a movable member extending into said path far enough to support the outgoing magazine bobbin until the time for its discharge, and while the bobbin is traversing the discharge path, said movable 70 member transmits motion to the filling thread clamping and parting instrumentality or cutter. Normally, each bobbin traverses the entire discharge path from the lowermost position in the magazine through 75 the shuttle into a receptacle used for receiving the empty or rejected bobbins, each bobbin remaining in the shuttle until nearly all of the thread on said bobbin has been put 80 into the cloth.

I claim as my invention:

1. In a loom, the combination with a bobbin magazine, a shuttle, and a movable filling thread parting instrumentality, of a movable member extending into the bobbin 85 discharge path and adapted to be actuated by the discharge of a bobbin from the magazine, and a rocking member intermediate said movable member and said parting instrumentality and adapted when oscillated 90 by said movable member to actuate said parting instrumentality whereby the filling thread may be parted.

2. In a loom, the combination with a bobbin magazine, a shuttle and a movable filling thread parting instrumentality adapted 95 to be reciprocated into and out of thread engaging position, comprising a stationary and a movable blade, a block carried by said movable blade and having a laterally ex- 100 tending pin, of a movable member extending into the bobbin discharge path and adapted to be actuated by the discharge of a bobbin from the magazine, and a rocking member intermediate said movable member and said parting instrumentality adapted to be oscillated 105 by said movable member, a laterally projecting finger on said rocking member adapted to engage said pin when the thread parting instrumentality is in thread engaging position, whereby the movable blade may be actuated and the filling thread parted.

3. In a loom, the combination with a bobbin magazine, a shuttle, and a movable filling thread parting instrumentality adapted 115 to be reciprocated into and out of thread engaging position comprising a stationary and a movable blade, a block carried by said movable blade and having upper and lower pins extending laterally in opposite directions, of a movable member extending into the bobbin discharge path and adapted to be actuated by the discharge of a bobbin from the magazine, and a rocking member intermediate said movable member and said parting instrumentality adapted to be oscillated 120 by said movable member, and having a finger adapted to engage said upper pin when the thread parting instrumentality is in thread- 125 130

- engaging position, and means for engaging the lower pin, as the thread parting blade is moved toward thread engaging position, to separate said cutting blades.
5. 4. In a loom, the combination with a bobbin magazine and bobbin transferring means, a bobbin support movable to release a fresh bobbin from the magazine, a shuttle feeler, thread parting and clamping means carried thereby, a block carried by one of the members of said parting and clamping means, a rock shaft having a finger adapted to engage said block, and means actuated by the bobbin support upon the actuation of the transferring means to oscillate said rock shaft and to cause the finger to engage said block and thereby close the thread parting and clamping means.
5. In a loom, the combination with a bobbin magazine and bobbin transferring means, a pivoted bobbin support movable to release a fresh bobbin from the magazine, a reciprocatory shuttle feeler having a stationary blade and a coöperating pivotally movable thread parting blade and clamping member, a block secured to said movable blade, and having oppositely disposed projecting pins, a rock shaft having a finger adapted to engage one of said pins when the shuttle feeler is in thread engaging position, an arm positioned in the path of an actuating member carried by the bobbin support, whereby the actuation of the transferring means in thrusting a fresh bobbin into the shuttle will oscillate said actuating member thereby rotating said rock shaft and causing the finger to close said coöperating thread parting blade and clamping member.
- 20 10. In a loom, the combination with a bobbin magazine and bobbin transferring means, a pivoted bobbin support movable to release a fresh bobbin from the magazine, a reciprocatory shuttle feeler having a stationary blade and a coöperating pivotally movable thread parting blade and clamping member, a block secured to said movable blade and having a laterally projecting pin, a rock shaft having a finger adapted to engage said lateral pin, an arm positioned in the path 15 of an actuating member and carried by the bobbin support whereby the actuation of the transferring means in thrusting a fresh bobbin into the shuttle will oscillate said actuating member thereby rotating said rock shaft and causing the finger to close said co-
- operating thread parting blade and clamping member.
6. In a loom, the combination with a bobbin magazine and bobbin transferring means, a pivoted bobbin support movable to release a fresh bobbin from the magazine, a reciprocatory shuttle feeler having a stationary blade and a coöperating pivotally movable thread parting blade and clamping member, a block secured to said movable blade, and having oppositely disposed projecting pins, a rock shaft having a finger adapted to engage one of said pins when the shuttle feeler is in thread engaging position, an arm positioned in the path of an actuating member carried by the bobbin support, whereby the actuation of the transferring means in thrusting a fresh bobbin into the shuttle will oscillate said actuating member thereby rotating said rock shaft and causing the finger to close said coöperating thread parting blade and clamping member, and means to engage the other of said oppositely disposed pins as the shuttle feeler is moved toward thread engaging position to separate said thread parting blade and clamping member.
- In testimony whereof I have signed my name, in presence of two witnesses, this fourth day of November, in the year one thousand nine hundred and thirteen.

CHARLES B. LANE.
